UNITED STATES PATENT OFFICE.

WILLIAM ELBERT TATE, OF WEATHERFORD, TEXAS.

FOLDING COOP.

SPECIFICATION forming part of Letters Patent No. 377,650, dated February 7, 1888.

Application filed November 10, 1887. Serial No. 251,850. (No model.)

To all whom it may concern:

Be it known that I, WILLIAM ELBERT TATE, of Weatherford, in the county of Parker and State of Texas, have invented a new and useful Improvement in Folding Coops, of which the following is a specification.

This invention is a folding coop or crate, which may be readily folded into a compact form for transportation or storage when empty, and which may be conveniently adjusted to open position for use and secured in such position when so desired.

The invention consists in certain features of construction and novel combinations of parts, as will be described and claimed.

In the drawings, Figure 1 is a top plan view, Fig. 2 a side elevation, and Fig. 3 a cross-section, of my coop as when ready for use. Fig. 4 is a perspective view of the device with the several parts opened. Figs. 5 and 6 are respectively side and end views of the coop folded up as for transportation or storage, and Fig. 7 is a detail view.

The "coop"—by which term I shall refer to the device, as it is especially intended for the shipment of fowls, such as chickens, ducks, and the like—consists of the bottom sections, A, the side sections, B B', the top sections, C C', the partition D, the ends E E, and the hinges and fastenings, as will be described.

The bottom, which is preferably formed of the sections A A', has such sections hinged together at their inner edges, so they may fold back onto each other. This hinge-connection in the construction shown is preferably formed of leaves F F and a pintle or rod, G, the leaves being parts of straps of iron which are secured to and extend across the under side of the bottom sections, operating as braces therefor, and also serving to provide sections of the hinges which connect the sides with the bottom sections.

Straps H H are extensions of the inner ends of the hinge-leaves F, which straps have their upper ends bent at h, forming hooks, which in practice lap over the base-rod of the partition from the opposite sides of such base-rod and secure the partition in place. The side B is hinged at its lower edge to the bottom, usually to the section A thereof, and is provided with the clasps or catches I, for securing the ends and the top. These catches

may be of the variety shown or of other suitable construction, and it is manifest that it would involve no departure from the broad principles of the invention to support the catches on the ends and top instead of on the side B. The side B' is hinged at one edge to the bottom, usually to the side edge of section A' thereof. The ends are hinged at one end to the opposite ends of the side B'.

The top sections, C C', are hinged together at their adjacent edges, the section C' being hinged to the upper edge of side B' and the partition D being connected with the sections C C' at the juncture of such sections. The connection of the partition with the top sections and the connection between the said sections is preferably effected, as shown most clearly in Figs. 3 and 4, by providing the partition at its upper edge or side with short arms or rods d, which project to the opposite sides of said partition and are pivoted at their ends to the top sections, as shown.

It will be understood that the arrangement of the parts shown in Fig. 4 is for the purpose of illustration, and that it is never necessary to so arrange the parts in the adjustment of the coop from the folded position to the position for use, or vice versa.

When the coop is in the position shown in Figs. 1, 2, and 3 and it is desired to fold it up, the catches should be released. The bottom may then be bent sufficiently to release the partition from the hooks h. The ends may be folded back against the side section, B', which section B' may be folded down against the bottom section, A'. The top sections and partition may then be folded together and down upon the side B' and the ends folded thereon. The side B can now be folded against the upper side of the section A, when sections A A' may be folded bottom to bottom on their hinge-connection, and the device will be in the compact form shown in Figs. 4 and 5.

A strap, J, is provided for securing the parts in the folded position, such strap being secured between its ends to one of the sections and having perforations near its ends to receive a pin driven in one of the bottom sections.

It will be seen that the partition, in addition to serving as a support or brace for the top, serves to divide the coop into two com-

partments, so that the fowls in the coop will be kept separated and cannot crowd together or pile up on each other in such manner as to be smothered in transit.

5 The ends fit in between the bottom, the top, and the sides, and also serve to brace the coop when in position for use. When in use, the top section, C, may be opened, if desired, without opening the rest of the top or disturbing the partition, and either end may be opened independently of the other.

10 The coop is strong and rigid in use, and when not in use may, as shown in Figs. 4 and 5, be folded into very compact form for transportation or storage. Also, by reason of forming the ends, sides, top, and partition of wire frames, the coop will be much lighter than the ordinary wooden coop, and consequently will cost less to ship either full or empty.

15 20 The side, end, and top sections and partition, being formed of wire or metal frames suitably braced, and having wire-netting formed across them, properly retain the fowls, and at the same time give ample air and ventilation, tending to keep the fowls free from disease.

25 It will be understood that in practice the sections or frames, sides, ends, and top, and the partition should be so netted as to properly confine the chickens, ducks, or other fowls 30 it is desired to coop.

In Fig. 7 I show a typical section in detail, it comprising the outside rods or frame, the cross-rods, and the diagonal rods.

The sections or frames may be so formed or 35 otherwise suitably closed as to retain the fowls.

Having thus described my invention, what I claim as new is—

1. The combination, in a coop, of the bottom, sides, and ends, the top formed in sections 40 hinged together, whereby one section may be raised without the other, and the partition dividing the coop into compartments and ar-

ranged at the juncture of the sections of the top, substantially as set forth.

2. In a folding coop, the combination of the 45 bottom, sides, ends, and top, the latter being formed in sections, and the partition connected with the top at the juncture of its sections, whereby to support such sectional top, substantially as set forth. 50

3. The combination, with the ends, the sides, the top, and the partition, of the bottom formed of sections hinged together and provided at their hinged or abutting edges with hooks for engaging and securing the lower edge of the 55 partition, substantially as set forth.

4. In a folding coop, the combination of the sides, the bottom, the end pieces, the top sections, and the partition having short bars or arms secured between their ends to the partition, projected to the opposite sides of said partition, and pivotally connected at their ends to the sections of the top, substantially as set forth. 60

5. In a coop, the combination of the bottom 65 sections hinged together and provided at their hinged or abutting edges with catches for securing the partition, the ends, the sides hinged to the bottom, and the top hinged to one of the sides and provided with the partition, substantially as set forth. 70

6. The improved coop herein described, consisting of the bottom sections, A A', hinged together, the side B, hinged to section A, the side B', hinged to section A', the ends E, 75 hinged to side B', the top sections, C C', the former being hinged to side B, and the partition connected with the top sections at the point of connection of the latter, substantially as set forth.

WILLIAM ELBERT TATE.
